FIG. 3.

UNITED STATES PATENT OFFICE

2,149,602

PUMP

Anthony G. Horvath, Dayton, Ohio, assignor to
The Dayton Pump & Mfg. Co., Dayton, Ohio, a
corporation of Ohio

Application December 24, 1937, Serial No. 181,504

7 Claims. (Cl. 103—42)

This invention relates to fluid dispensing equipment and particularly to gasoline filling station equipment.

The object of this invention is to provide a motor driven pump the motor of which is remote from the pump, the pump being located in an underground tank.

It is an object of this invention to provide in such an arrangement a pump that is self-priming, that does not pump air, and in which the valve construction may permit slight leakages without rendering the pump inaccurate in service.

It is an object to provide such a valve arrangement in association with the pump in the remote buried tank so that such a valve does not need frequent repairs and, when it wears, the slight leakage resulting will not be serious.

It is a further object to provide in such an arrangement a valve control that is readily accessible and can be located in the motor pit where it can be readily reached. Such a valve is utilized to prevent the draining of gasoline back between the tank and pump.

It is a further object to provide a third valve which is also accessible that relieves the pressure beyond the check valve just mentioned into the interior of the tank through the space between the impeller and the impeller shaft pipe of the pump. This arrangement makes the relief valve accessible for adjustments to different pressures. By placing the pressure relief valve adjacent a location in the discharge line outside of the storage tank and remote therefrom, the various advantages indicated result.

Referring to the drawings, Figure 1 is an elevation with the tank partially in section and with the ground and pump pit in section, showing generally the arrangement of the apparatus.

Figure 2 is a detail section from a point just below the motor to the bottom of the pump.

Figure 3 is a detail elevation of the motor and the upper part of the pump and valve construction showing the upper pressure relief check valve and associated valve mechanism.

Figure 4 shows in detail a section through the pump and the primary check valve which prevents the flow back of fluid and prevents the pumping of air.

Figure 5 is a section through the pump to show its nature on the line 5—5 of Figure 4.

Referring to the drawings in detail, 1 is the ground on which is mounted a concrete platform 2, formed into a concrete pit 3 in which is mounted the motor and a portion of the top of the piping, etc. On top of the ground is mounted the

dispensing apparatus 4 and 5 having the usual dispensing hose and nozzles 6 and 7. Such hose and nozzles 6 and 7 are fed by the pipes 8 and 9 which are connected to the outlet 10 of the pump mechanism hereinafter described. An actuating motor 11 is brought into electrical circuit through the wires 12 and 13 by the lifting of the nozzle 6 or 7 from the switch 14.

When this takes place the motor is brought in circuit and rotates its armature shaft 15 and in turn the impeller shaft 16. Around this impeller shaft is a spring packing 17 to seal the shaft from the passage of lubricant 18 in the lubricant chamber 19. This shaft is hollow. It is connected at its lower end by the keys 20 to the pump impeller shaft 21 on which are mounted the impellers 22 of the pump that travel inside of the stator guides 23 of any conventional centrifugal pump. The bottom of the pump impeller shaft rides upon a ball bearing 24. The tank 25 in which this pump is submerged contains the gasoline 26 that enters through the strainer 27 into the bottom of the pump and its casing 28 which supports the stator guides 23.

At the top of this pump there is a partition 29 having ports 30 that are closed by the pump primary check valve 31 that is spring pressed downwardly by the spring 32. The pressure of the fluid pumped by the pump lifts this check valve. When the pump stops, the spring plus any pressure of fluid above the pump closes the valve. This prevents the pump from pumping air. The port 30a is used for evacuating the air from the pump as it provides a means of escape for the entrapped air so that the pump will pump, primarily, the liquid which in turn lifts the valve 31.

If there are any slight inaccuracies in the valve, such leakages as result are small and not serious. Therefore, it is seldom necessary to have access to this remote valve. The fluid so pumped is pumped through the port 33, upwardly through the pipe 34 through a space 35 formed by the pipe 34 and the inner pipe 36, the function of which consists of a protection for the drive shaft 16 and for other purposes hereinafter specified. The gasoline so pumped travels to the top of the pipe 34 through the space 35, whence it turns at right angles into the chamber 37, and thence passes into the laterally disposed valve chamber 38 within the casing 39.

The pressure lifts the valve 40 which is rotated by the wings 41 and is limited in its upward movement by the stud 42. The gasoline passes into the chamber 43 and thence out the discharge opening 10 to be dispensed as hereinafter described. This second valve is a check valve to

45

50

55

prevent the draining of gasoline from the dispensing pumps back to the tank and is accessible. It is located within the pit 3 and can be readily adjusted for accuracy by removing the screw plug 5 42a. The opening thus uncovered by removing the screw plug 42a is larger than the valve 40 so that it can be readily removed, adjusted and replaced. A spacing pipe 60 extends between an upper collar 61, fastened to the casing 39, and 10 a lower collar 62 surrounding the opening in the tank 25, such spacing pipe serving through said collars to connect the casing 39 with the tank, and acting as a protecting covering for the pipe 34 between the tank and casing.

15 The third valve construction which is one of the essential features of this pump is the check valve 44 which is normally spring pressed downwardly by the spring 45. Access to this valve is secured by removing the plug 46. This valve is 20 located to control the passage of fluid through the passageway 47 leading from the chamber 37 and the passageway 48 leading from the chamber 49. This chamber 49 communicates with the space 50 formed between the tube 36 and the drive shaft or 25 tube 16. The bottom of this space 50 communicates with the drain opening 51 for the return of gasoline to the tank 25. By adjusting the screw plug 46 and the compression of spring 45, an accurate adjustment can be effected readily from 30 within the pit 3 to regulate the pressure of delivery by the pump so that any excess over that pressure will be relieved by the relief valve 44 returning the by-passed gasoline back into the tank. This pressure relief valve may be located beyond 35 valve 40 so that the by-pass pressure will return from chamber 43 into the space 50 or it may be arranged as indicated.

It will be understood that it is desired to comprehend within this invention such modifications as come within the scope of the claims and the 40 invention.

Having thus fully described my invention, what I claim as new and desire to secure by Letters Patent, is:

1. In a fluid dispensing apparatus, a source of supply of liquid to be dispensed, a pump immersed therein, a delivery pipe extending from the pump to a point of discharge, and a return pipe arranged concentrically within said delivery pipe and forming a connection between the pressure relief valve and the tank, a check valve adjacent the pump to prevent the drain back of liquid through the pump into the tank, a pressure relief valve outside of the tank adapted to return the liquid so pumped into the tank when a predetermined excess pressure has been created by the pump, said relief valve being located at a point remote from said pump and said tank outside of the tank.
2. In a gasoline dispensing apparatus, a motor and valve pit therebeneath accessible from the top of the ground, a remotely located gasoline tank therebeneath, a centrifugal pump located therein, means in said pit for driving said pump, means connecting said driving means to said pump, a fluid delivery pipe from said pump surrounding said connecting means and extending into said pit, a bottom check valve in said tank above said pump, a pit check valve at the top of 65 said fluid delivery means accessible from said pit to prevent the return of fluid to the tank from a dispensing apparatus to which the fluid is being delivered, a by-pass check valve at the top of said fluid delivery pipe accessible for adjustment from said pit, a drain-back pipe leading

therefrom back to said tank, a spacing pipe connecting said tank and said pit, and means on top thereof for supporting said fluid delivery pipe and drain back pipe in concentric relationship within said tank.

3. In combination, a tank, a centrifugal pump mounted therein, a remotely actuated drive shaft for said pump, a tubular casing for delivery of fluid from the pump, an interior casing spaced therefrom for returning fluid from the top of the first casing back to the tank, said interior casing opening into said tank at its lower end and both of said casings surrounding said drive shaft, a check valve between the pump and the first mentioned casing, a pressure operated by-pass valve at the top of the first and second mentioned casings for regulating communication therebetween, and a third check valve at the outlet of the first mentioned casing to control the delivery of fluid from the tubular casing.

4. In combination, a tank, a centrifugal pump mounted therein, a remotely actuated drive shaft for said pump, a tubular casing for delivery of fluid from the pump, an interior casing spaced therefrom for returning fluid from the top of the first casing back to the tank, said interior casing opening into said tank at its lower end and both of said casings surrounding said drive shaft, a check valve between the pump and the first mentioned casing, a pressure operated by-pass valve at the top of the first and second mentioned casings for regulating communication therebetween, a third check valve at the outlet of the first mentioned casing to control the delivery of fluid from the tubular casing, and means associated with 30 said pump adjacent the top thereof for permitting the escape of air from the pump.

5. In combination, a storage tank for liquid, a remote chamber for containing a motor and valve mechanism, a spacer pipe between said tank and chamber, a concentrically arranged pipe supporting a pump and suspended by said spacer pipe, a valve housing in communication with said supporting pipe, a drain back check valve in said housing between the point of discharge therefrom and said pump pipe, a concentrically arranged drain back pipe within said pump pipe communicating with said tank, a by-pass valve in said housing communicating on one side with said pump pipe and on the other side with the drain back pipe, a pump on the end of said pump pipe in said tank, a motor shaft concentrically arranged within said drain back pipe connected to said pump at one end and to a motor mounted on said housing at the other end, and a second check valve at the bottom of said pump and drain back pipes between the pump and pump pipe.

6. In combination, a tank, a pump therein, a fluid delivery pipe supporting said pump extending out of the tank remotely, a pressure operated by-pass valve at the top of said pipe, a drain back pipe concentrically arranged relatively to said delivery pipe in communication with the discharge side of the by-pass valve and with said tank, a check valve between said pump and the bottom of the fluid delivery pipe, and a relief port direct from said pump to said tank between the top of the pump and the bottom of said pump check valve, and yielding means for normally maintaining said check valve in closed position until said pump lifts the valve by predetermined fluid pressure pumped by it.

7. In combination, a motor driven centrifugal pump, a tank in which said pump is located, a delivery pipe connected to the pump, a primary

check valve in said delivery pipe to prevent drain back of the fluid, a drain back pipe arranged within and concentric with said delivery pipe communicating with the top of the delivery pipe and with said tank, a pump shaft for said pump located within said drain back pipe, a motor above said pipes connected to said pump shaft which is connected to the pump below said pipes,

a secondary check valve at the top of said delivery pipe, a pressure relief valve adjacent the top of said delivery pipe between it and said drain back pipe, and means communicating therewith for returning by-passed pumped fluid from the top of the delivery pipe to the top of the drain back pipe and thence back to the tank. 5
